UNITED STATES PATENT OFFICE

2,009,185

WATER-MARKING

William P. McCorkindale, South Hadley Falls, Mass., assignor of one-half to The McCorkindale Company, Holyoke, Mass., a corporation of Massachusetts, and one-half to American Writing Paper Company, Inc., Holyoke, Mass., a corporation of Delaware

Application April 4, 1934, Serial No. 718,972

8 Claims. (Cl. 92—48)

This invention relates to improvements in paper manufacture and is directed more particularly to improvements in process for water-marking paper and the product thereof. This application is a continuation in part of an application for Letters Patent of the United States executed by me on March 14, 1934, Serial Number 718,971, filed on April 4, 1934.

The principal objects of the invention are directed to the provision of a novel process of, and apparatus for, producing water-marks in paper. The novel features of the invention facilitate the producing of new and novel effects heretofore unknown in the paper-making art.

According to the present practice of forming water-marks and other markings in paper, a dandy roll bears on a formed web of paper which is carried by a Fourdrinier wire or the like to produce the mark by shifting the fibers. According to this invention, water-marks are formed as the paper-making fibers are formed into a web when taken on by a foraminous paper-making surface. Where a dandy roll is used, the characteristics of the water-marks produced thereby are more or less limited, but according to this invention various and numerous novel effects are possible.

Various novel features and advantages of the invention will be hereinafter more fully referred to in connection with the accompanying description of the invention, reference being had to the accompanying drawing wherein:

Fig. 1 is a plan view of a portion of a foraminous paper-making member having means associated therewith to produce a water-mark.

Fig. 2 is a plan view of a section of a sheet showing a water-mark therein produced by the water-marking features shown in Fig. 1.

Fig. 3 is a plan view of a device for carrying a sheet or web of paper in the nature of a foraminous member having means associated therewith for producing a water-mark.

Fig. 4 is a plan view similar to Fig. 2 showing a portion of a sheet of paper having a water-mark produced by the water-marking means disclosed in Fig. 3.

Fig. 5 is a sectional more or less diagrammatic elevational view showing certain parts of a paper-making apparatus with certain of the water-marking means of the invention, and

Fig. 6 is an inverted plan view of the paper-making element shown in Fig. 5.

Referring now to the drawing more in detail, the invention will be fully described.

In Fig. 5 there is shown in section a paper-

making member 2 of the same general type as that shown in my pending application executed by me on March 14, 1934, and identified as Serial No. 718,971, filed April 4, 1934. This includes a receptacle 4 having a perforated plate 6 over which is disposed a foraminous paper-making surface 8 which may be in the form of wire screen, wire cloth, or the like.

A stuff vat is shown at 10 which, as in the application referred to, contains paper-making material into which the foraminous face of the making member 2 is submerged. The member 4 is then subjected to suction by means of a pipe or conduit 12 connected to a source of suction whereby the paper-making material is drawn onto the foraminous surface.

A carrier 5 is shown in Fig. 3 which, as in the application referred to, comprises a foraminous member 9 supported by a frame 7. The paper formed on member 8 is deposited on the carrier 5 by suction, as is explained in said application.

The water-marking features to be described are preferably used with the apparatus just briefly described.

In Fig. 1 a section of the foraminous surface 8 of a paper-forming member such as member 2 is shown and according to the invention there is provided therein a depression or depressions 14 which are in the shape or form of the watermark it is desired to produce in the paper. In the example shown, the depression is in the shape of the letter "A" and may be formed by depressing or indenting the foraminous surface slightly. The water-mark is produced in the paper by drawing the paper-making material onto the foraminous surface and into the depression by suction.

The sinking of the letter "A" into the foraminous surface causes relatively more of the fibers to be deposited in the depression than elsewhere on the foraminous surface whereby paper-making material is relatively more dense over the depression than in the main body of the paper S. This is indicated by 15 in Fig. 2 and it will be seen the water-mark appears darker than the main body of the sheets.

In another way, a water-marking element such as 16 is secured to the foraminous surface 8 and is slightly raised above the plane thereof. Thus, as the paper-making material is drawn onto the foraminous surface, there is produced a watermark 17 which is lighter than the main body of the sheet since there is a less amount of fibers overlying the element than elsewhere on the foraminous surface.

It is seen, then, that I make it possible to provide water-marks which are relatively lighter and darker than the main body of the sheet and which may be of various designs and shapes 5 by virtue of the fact that the fibers are arranged in such a way as to produce the effects.

In Fig. 3 the foraminous member 8 of a carrier 5 has associated therewith a water-marking element 18 which is preferably formed of some 10 material adapted to contain and release a coloring substance such as a dye or the like. The characteristics of the element 18 are such that the coloring substance therein is released so as to be absorbed by the paper. That is, when the 15 moist paper S' formed on the surface 8 is superposed thereover and transferred to the carrier 5, the fibers overlying the marking element absorb to some extent the coloring substance incorporated in the element 18.

The element 18 may be of fabric, blotting paper 20 or of some more or less porous material capable of containing and releasing coloring. This is so that when the paper is deposited on the foraminous surface of the carrier, the fibers are caused 25 to absorb the coloring substance whereby the sheet or web of paper carries a water-mark which corresponds in design to the element 18 and which is colored or tinted according to the coloring substance associated with and released by 30 said element.

Blotting paper which is saturated with dye has been found to be particularly adapted for the purpose of the invention, although I do not wish to be so limited. When a sheet of paper is thus 35 deposited on and removed from the carrier, there is provided a colored water-mark in the shape of the element 18. During the course of the drying of the sheet S', the coloring penetrates and sets in the sheet so that there results a sheet having 40 a colored water-mark incorporated therein. This has been found to be very useful in connection with the manufacture of paper used for certain purposes and it will be readily appreciated that the elements or element 18 may take various 45 forms and shapes and that they may embody substances within a wide range of colors, all to the end that numerous novel effects may be obtained.

It is desirable that water-marking elements 50 be provided which may be readily and easily attachable and removable from the foraminous surface so that water-marks may be interchanged to facilitate the production of paper having various and numerous water-marks.

In the form of the invention shown in Figs. 5 and 6, a removable water-marking element or 55 elements 30 are provided. A block member 32 is provided which preferably extends downwardly through the plate 6 and has its forward face 60 against the foraminous surface 8. The upper side of the block extends upwardly through the member 4 and a magnet 34 of any well known form is employed for placing on the block 32 so that the water-marking elements 30 are held 65 magnetically against the foraminous surface 8.

The water-marking element or elements 30 may, of course, take any form desired and by removing the magnet from the block the element or elements 30 may be released so that others 70 may be located on and held in place on the foraminous surface by magnetic action.

In the manufacture of paper it is often desirable to produce small lots of paper having certain water-marking. This is, of course, difficult 75 and commercially impractical where dandy rolls

are employed or where the water-marking elements are in some manner attached to the foraminous surface. According to the novel features of this invention, the water-marking elements may be changed at will and thus it is possible by changing the elements to readily and easily produce small lots of paper having special water-marks.

While I have described the invention in great detail and with respect to a preferred form thereof, it is not desired to be limited thereto since many changes and modifications may be made therein without departing from the spirit and scope of the invention. What it is desired to claim and secure by Letters Patent of the United States is:

1. A process of producing water-marked paper which consists in depositing paper-making material on a non-rounded foraminous surface by suction, the said surface having a depression 20 therein in the form of a water-mark being produced whereby the water-marked portion of the paper is of greater density than the main body thereof.

2. In an apparatus for producing water-marked 25 paper, the combination of a member provided with a non-rounded foraminous surface having a depression therein in the form of a watermark and suction means for depositing paper-making material on said surface.

3. An apparatus for producing water-marked paper comprising, a member having a foraminous surface provided with a water-marking element magnetically held thereon.

4. An apparatus for producing water-marked 35 paper comprising, a member having a foraminous surface provided with a water-marking element on one side thereof and a magnet on the other side thereof for holding said water-marking element against said one side of the surface.

5. An apparatus for producing water-marked paper comprising in combination, a receptacle member provided with a foraminous surface having a water-marking element on one side thereof and a magnetized member extending from the 45 other side thereof through said receptacle for holding said element against said one side of the surface.

6. An apparatus for producing water-marked 50 paper comprising, a paper-making member including a receptacle having a foraminous surface and means for depositing paper-making material onto said surface by suction, said surface being provided with a water-marking element magnetically held thereon.

7. An apparatus for producing water-marked 55 paper comprising, a paper-making member including a receptacle having a foraminous surface and means for depositing paper-making material onto said surface by suction, said surface being provided with a water-marking element on one side thereof and a magnetized member extending from the other side thereof through said paper-making member for magnetically holding said 60 element on said one side.

8. The process of producing paper having a colored water-mark therein which consists in, 65 depositing a wet sheet of paper-making material on a substantially flat foraminous surface by 70 means of suction, which foraminous surface has a water-marking element thereon which releases coloring material as said sheet is deposited on said surface.

WILLIAM P. McCORKINDALE.
